UNITED STATES PATENT OFFICE.

W. RACE, OF SENECA FALLS, NEW YORK.

ARRANGEMENT OF CATCHES IN THE UPPER SASH OPERATED BY MOVING THE LOWER SASH.

Specification of Letters Patent No. 8,186, dated July 1, 1851.

To all whom it may concern:

Be it known that I, WASHBURN RACE, of Seneca Falls, in the county of Seneca and State of New York, have invented a new and useful Improvement in Window-Sash Checks and Fasteners; and I do hereby declare that the following is a full, clear, and exact description thereof, reference being had to the accompanying drawings, making 10 a part of this specification, Figure 1 being an elevation of a window with both sashes closed, as seen from the inner side; Fig. 2, a vertical section of the same at the red line in Fig. 1, and Fig. 3, a vertical section 15 through the center of a window in which the upper sash is partly lowered and the lower sash partly elevated.

The nature of my invention consists in constructing and arranging the catches 20 which hold up the upper sash of a window in such manner that they can be operated to release the upper sash and allow it to open, or to secure this sash in any desired position either open or closed, by means of the lower 25 sash of the window and without applying the hands either to the upper sash or to its catches.

In the accompanying drawing A is the upper and B is the lower sash. The lower 30 sash is fitted with a catch *d* of any suitable approved construction.

The upper sash A is fitted with two catches *e*, *e*, whose shorter arms being borne against the center slats *g* of the window frame, by 35 the weight of their longer arms, engage in suitable notches *i*, *i*, formed in those center slats. The longer arms of these catches depend below their pivots and their positions with respect to the lower sash of the window 40 is such that if this sash be shoved upward its top bar will strike the longer arms of the catches of the upper sash and raising them will disengage their shorter arms from their notches in the center slats. If then the lower 45 sash be let down slowly the upper sash, being released by the withdrawal of its catches from their respective notches, will descend

with it. If the descent of the upper sash is to be stopped, the lower sash is moved suddenly downward, by which means its top 50 bar is drawn away from the longer arms of the upper sash catches, which being no longer supported will turn down by their own gravity and force their respective shorter arms into the next succeeding notches 55 of the center slats, thus stopping the further descent of the upper sash.

When the upper sash is to be raised the lower sash is shoved upward; in its upward movement its top bar strikes the upper sash 60 catches and detaches them from their notches; if now the lower sash be moved further, it will carry the upper sash with it to its uppermost position. The lower sash is then moved suddenly downward, by which 65 means, as before stated, the upper sash catches will be allowed to engage with their respective notches in the center slats and thus secure the upper sash in its uppermost position. It will be perceived that by this 70 method of arranging the upper sash catches they are operated to release or to secure their respective sash by the movement of the lower sash, which being within the reach of the operator can be readily raised or lowered. The upper sash is thus readily opened 75 or closed without requiring the operator to stand upon a chair or other support to enable him to reach up to the catches of the upper sash; as two catches also are employed the sagging of the upper sash is effectually prevented.

What I claim as my invention and desire to secure by Letters Patent is—

The arrangement herein described of the 85 catches and window sashes for the purpose described.

In testimony whereof I have hereunto subscribed my name.

WASHBURN RACE.
